WARDROBE CASE

William Wintz, Oshkosh, Wis., assignor to Oshkosh Trunks, Inc., Oshkosh, Wis., a corporation of Wisconsin

Application November 19, 1932, Serial No. 643,343

3 Claims. (Cl. 190—41)

This invention relates to a hand carried luggage case of the wardrobe type.

The main object of my invention is to provide the case with a garment carrying element or fixture of such a construction that one or more men's suits including coat, vest and trousers, may be readily and conveniently carried in folded form in one section of the case, as for instance, the cover or lid thereof, without being wrinkled or creased.

Another object of my invention is to so construct and arrange this fixture in the case that conventional form or garment hangers of the flat type shaped to fit the shoulder and neck portions of a coat and vest and having a cross-bar for the trousers may be used to attach each suit to the fixture.

A further object of my invention is to provide novel means for detachably connecting the garment hangers to the carrying element or fixture, said means comprising interengageable parts on the hanger or hangers and the element, respectively.

A further object of my invention is to provide the carrying element in the form of a support which when in lowered position over the body of the case will support the garments in flat wise relation thereon.

A further object of my invention is to provide this support with an extensible section which when extended will be so angularly disposed to the support that the latter will be held above the body of the case and in substantially horizontal position thereover, so that the support if an open frame will prevent the garments from sagging or dropping into the body of the case.

A further object of my invention is to employ this extensible section as the means whereby the element may be grasped for swinging it into and out of the lid or cover of the case and also to lift the free portions of the garments on the outer side of the element when lowering it over the body of the case.

A further object of the invention is to provide the element at its outer or free end with means, preferably in the form of an attachment, by which the folded portions of garments over the outer end of the element, when more than one man's suit is attached thereto, will be distributed along the length of the element to reduce the bulk of the material where folded over the element. With this means in the form of an attachment, it may be removed from the element to permit an underlying suit to be attached or removed from the element.

In the accompanying drawings, Fig. 1 is a perspective view of a luggage case equipped with a garment carrying element of my invention, the case being shown in open position and with the element, with a single suit thereon, in lowered position.

Fig. 2 is a vertical sectional view taken through the open case, the garment carrying element with two suits thereon being shown in raised position in the lid or cover of the case in full lines; the element without garments thereon being shown in lowered position over the body of the case in dot and dash lines;

Fig. 2^a is a fragmentary perspective view illustrating the manner in which the element is pivotally and releasably secured in the case;

Fig. 3 is a horizontal plan view, partly in section, taken on line 3—3 of Fig. 2;

Fig. 4 is a plan view showing the means for detachably connecting the garment hangers to the element;

Fig. 5 is a sectional view taken on line 5—5 of Fig. 4;

Fig. 6 is a top plan view, with parts in horizontal section, showing the manner in which the auxiliary or supplement bar, to be hereinafter described, is releasably attached to the element;

Fig. 7 is a vertical sectional view taken on line 7—7 of Fig. 6; and

Fig. 8 is a side view of the assembly shown in Fig. 6, with parts broken away and in section, respectively.

As shown in the drawings, the case to which my invention is applicable is of the box type having hingedly connected, rigid body and lid or cover sections 1, 2. The hinge connection 3 between the sections is at the rear of the case, being along the upper edge of the rear wall 4 of the body section as shown in Fig. 2. The cover 2 when closed fits against the upper edge of the body section and is releasably secured thereto by latch and bolt means 5, 6 on the front wall 7 of the case as in devices of this general character.

The garment carrying element 8 is designed to fit within the cover 2 and occupy the greater portion thereof. Said element is in the form of a rectangular metal or steel frame having side members 9, 9 and end members 10, 11. The latter are integrally connected with the side members, the frame being formed from a single metal strip. A wood or other non-metallic bar 12 is secured to the end member 11 which is at the outer or free end of the frame. This bar is substantially cylindric in cross-section to prevent creasing or

wrinkling of the garments folded thereover in the use of the frame.

The frame 8 is pivotally and releasably mounted in the lid or cover 2 adjacent the hinged connection between the lid and the cover so that the frame may be swung into and out of the cover and when out of the cover occupy a lowered position over the top of the body section as shown in Figs. 1 and 2. The mounting employed comprises a pair of co-operating members at each side of the frame. These members, as shown in Fig. 2a, comprise a U-shaped metal fastener 13 pivoted at 14 to the adjacent side of the frame and a bracket 15 secured in the lid or cover 2 on its side wall. Each bracket has a recess 16 to receive the tongue section on the outer side of the co-operating fastener 13. The parts 13 when inserted into the bracket 15 are held stationary and permit the frame to turn on the pivots 14 which are in axial alignment. The brackets are arranged in the lid or cover 2 to have their recesses 16 vertical when the lid is raised and with the parts 13 engaging the brackets from above, the frame may be readily and easily removed from the case when desired. The parts 13 and the brackets 15 may have interengaging bosses and recesses to hold the frame from accidental release from the lid.

For attaching one or more men's suits, including coat, vest and trousers, to the frame, I provide garment hangers 17, one for each suit. These hangers are of the conventional flat type, each having neck portion 18, diverging side or shoulder engaging portions 19, 19 and a cross-bar 20. These parts are in the same plane and are preferably integrally connected by cutting the hanger from a flat sheet which may be of a single layer or one or more layers when in laminated form. A U-shaped metal bracket 21 is rigidly attached to the rear bar 10 of the main frame midway the ends thereof and extends into the space within the frame, as shown in Fig. 5. A rivet 22 fastens the bracket to the frame, the bracket being shaped to straddle the bar 10 of the frame over its outer side as shown. The legs of the U are connected on the inner side of the bar by a pin 23 which constitutes one of the members by which the hangers 17 are attached to the frame.

The attaching means for each hanger 17, comprises a latch member 24 pivoted intermediate its ends, on the neck portion 18 of the hanger as shown in Fig. 4. The latch member is provided adjacent one end with an arcuate slot 25 opening through one side of the member to engage the pin 23 on the bracket 21 when the member is swung into engagement with the pin. The hanger has a slot 26 in its neck portion to receive the pin to facilitate the application of the hanger thereto. The slot is not much wider than the pin to reduce lateral shifting of the hanger. The outer end of the neck portion of the hanger fits close to the bar 10 and thus undue swinging of the hanger about the pin is avoided. (See Fig. 4.)

The end of the latch member 24 opposite the slot 25 is made hook shaped, as at 27, to provide a handle for swinging the latch member into and out of engagement with the pin and also to provide means for suspending the hanger with or without garments thereon in a clothes closet on a hook, rail or bar when the hanger is out of the case as indicated by the dot and dash line position of the latch in Fig. 4. Each hanger 17 is attached to the frame 8 in the manner herein described, and with the pin 23 long enough two or more hangers may be attached to the frame.

The hangers are in super-imposed relation when attached to the frame and the suits thereon are in the same relation when on the frame. In the drawings I have shown the frame constructed to accommodate two suits, the pin 23 being long enough to accommodate two hangers 17. 5

The frame 8 is provided at its outer or free end with an extensible section 28 which as shown in the drawings is also formed from a single strip of metal preferably steel. This section is U-shape 10 in form and is arranged to straddle the outer end of the main frame. The side members 29, 29 of the section are pivoted at 30 to the main frame to the rear of its cross-bar 12. The inner ends of the members 29 continue for a short distance beyond the pivots to engage stops 31, 31 in the form of rivets on the sides of the main frame when the section is in fully extended position beyond the same. The inner ends of the side members 29 are bent to be so angularly disposed to the 20 remaining portions of the members that when they engage the stops the section 28 will extend at a downward inclination to the main frame and by contact with the body 1 of the case where it crosses it hold the main frame in a substantially 25 horizontal position as shown in Figs. 1 and 2. The advantage of this is that the garments supported on the upper side of the main frame are prevented from sagging or dropping down into the body of the case for contact with the smaller 30 articles packed therein. To facilitate supporting the portions of the garments between the hangers 17 and the bar 12, I provide the main frame with a rigid cross-member 32 of wood or other light material. Said member has metal end pieces 35 which engage over the side arms 9 of the main frame and are riveted thereto as shown.

Attached to the outer end of the main frame is an auxiliary or supplemental cross-bar 33 over which the second suit on the frame folds when two suits are attached to the main frame. This bar is preferably of wood or other light material and is attached to a support in the form of a metal strip 34, the end portions 35 of which are bent at right angles to the bar and are insertable 45 in sockets carried by the main frame at the opposite sides thereof as shown in the drawings. These sockets comprise metal sleeves 36, 36 riveted to the main frame about the side arms thereof, as shown in Figs. 6 and 7. The ends of the side arms 9 to which sleeves are attached are offset inwardly to position the end portions 35 of the supplemental bar in line with the side arms when attached thereto as shown in Fig. 6. The end portions 35 have a fairly snug fit in the sockets 36 and thus the supplemental bar is releasably secured in place. Metal discs 37, 37 are provided at the ends of the bar 33 to prevent the folded portions of the garments thereon sliding over the ends of the bar to be caught or torn 55 between the main frame and its pivoted extension 28. These discs have laterally projecting flanges 38, 38 which may contact flatwise with the rear wall of the lid 2 when the frame is swung into 60 the same.

To pack one or more suits in the case, the latter is opened, the frame lowered, and the hangers 17 are removed. The suits are separately placed on the respective hangers, and the latter are returned one at a time to the frame 8. The first suit returned is attached to the frame through the latch member 24 on its hanger. The suit is adjusted over the top of the frame and extends over the bar 12 at the outer end of the frame. 70 75

The supplemental bar 33 has previously been removed from the frame and the suit may extend over the permanent bar 12 and out of the case over the extension 28. If a second suit is to be packed on the frame, the supplemental bar 33 is replaced, and the suit after being attached to the frame by its hanger 17 is adjusted over the first suit and extends out of the case over the extension 28. The garments being longer than the distended frame, extend out of the case beyond the front wall 7 thereof and hang out of the case over the cross-bar 28^a at the outer end of the extension 28. As this extension projects beyond the wall 7, its cross-bar 28^a keeps the garments out of contact with said wall and the handle 38^a and the locking devices 5 and 6 thereon, as shown in Fig. 1. Thus the garments are prevented from being soiled by contact with said wall or any of the fixtures thereon or from being torn or injured by said fixtures which are usually of metal and present more or less sharp edges at the boundaries thereof.

In locking the hangers 17 to the frame 8, the slots 25 in the latch members 24 by reason of their arcuate shape exert somewhat of a cam action on the pin 23 when swung into engagement therewith and draw the hangers against the hangers, the pin and the latch members prevent displacement of the hangers when locked to the pin. With the bottom flange of the bracket 21 on the under side of the hangers and supporting them, and with the latch members 24 beneath the upper flange of the bracket, the hangers are maintained in the general plane of the main frame even when free of garments. Thus shifting of the hangers with respect to the frame is prevented whether packed or not and when packed the garments on the hangers are held against lateral displacement when raised into the lid or cover 2.

To raise the garments into the lid or cover 2, the main frame 8 is lifted by the extension 28. As the frame is swung upward, the outer bar 28^a of the extension lifts the tail ends of the garments above the body 1 of the case and prevents them from trailing over the articles packed in said body. When the main frame reaches its upright position in the lid, the extension 28 is lowered against the front side of the frame, thus causing the garments to fold over the bars 12 and 33 at the upper end of the frame and hang down on the outer side of the same with the extension in between. With the extension 28 so positioned, it is retained by the garments against the main frame.

To hold the frame with the garments thereon in the lid 2, I may employ any desired form of fastening or holding means. Such means as shown in the drawings comprises a flexible cover or curtain 39 secured in the lid 2 at its upper end by a metal strip 40. The curtain has a length to extend close to the lower end of the main frame and is there provided with a flexible metal rod 41, the ends of which project beyond the sides of the curtain and are engageable with keepers 42, 42 on the side arms of the main frame adjacent the inner ends of the same. These keepers are disposed to be on the outer side of the frame when it is raised in the lid and when in plate form, as shown in the drawings, are riveted to the main frame and have spaced notches 43 along the outer edges thereof. These notches enable the rod 41 to be engaged with keepers at various points along the length of the same and thus enable

the desired tension to be placed on the curtain for holding the main frame in the lid and the garments compacted or compressed thereon. The curtain covers the garments and prevents them from sagging or contacting with the articles in the body of the case when the lid is closed.

With the frame mounted in the lid of the case, the suits may be readily packed in the case and be supported therein in folded form without wrinkling or creasing. With the suits so packed, it is obvious, that they will not interfere with access to the body of the case in which are packed those articles usable to a more frequent extent than the garments packed in the lid. Thus the case may be opened and closed without hindrance by the garments packed in the lid and free access may be had to the articles in the body of the case without hindrance by the garments in the lid.

To remove the suits from the case, the curtain is released from its keepers and folded back over the upper edge of the lid as shown in Fig. 1 after the lid has been raised. The extension 28 is grasped and lifted and at the same time is drawn outward to swing the main frame out of the lid. After the main frame is brought to lowered position over the body of the case, the uppermost suit is accessible and by releasing the latch member 24 from the pin 23, the hanger with suit thereon may be removed. If the lower suit is to be removed, the supplemental bar 33 is removed and the lower suit freed for removal from the case.

The supplemental bar 33 not only serves to hold the lower suit on the frame but also provides means for distributing the bulk of the material at the folds along the length of the frame. This is brought about by having the bars in spaced relation in the direction of the length of the frame thereby reducing the bulk of the material at the outer end of the frame and allowing the frame with both suits thereon to fit within a relatively shallow lid. Moreover, by this arrangement practically all of the available space within the lid is occupied by the garments on the frame with the result that none of this space is wasted, which would be the case should all the garments on the frame be folded over one bar at the outer end of the frame. In such case, it would be necessary to provide an exceptionally deep lid to accommodate the bulk of the material at the fold, with the necessity of making the body of the case shallower and therefore hold less and in fact would be unsuitable for a hat and other articles which have considerable height. In distributing the bulk of the garments at the fold over the outer end of the frame in accordance with my invention it is possible to retain the depth necessary for the body of the case and also apply my invention to cases which for commercial purposes must be limited to a height which will permit them being placed under a Pullman berth. Furthermore, with the arrangement of my invention, the lid or cover section of the case is maintained in such proportion to the deeper body of the case that the case will not tip over backward when opened with a full packing of garments in the lid of the same.

With a case equipped with garment supporting fixtures or means of my invention, as herein described and shown, the case may accommodate one or more men's suits in the lid of the case. When only one suit is to be packed, the suit may be folded either over the permanent bar 12 or over the supplemental bar 33. If the permanent bar is used, the supplemental bar is replaced on the frame after the suit is in place, as shown in Fig. 1.

While I have shown and described herein the application of only two garment hangers to the garment carrying frame, yet it is obvious that it would be within the scope of my invention to provide a construction accommodating more of such hangers whereby more than two suits could be attached to the frame. Ordinarily, the arrangement for two suits would satisfy the needs of most travelers and of course a construction could be arranged to carry more suits if required, it being possibly essential in such case to have a deeper lid, the carrying and garment attaching structure however remaining substantially the same as herein shown and described. The extension 28 is provided with a cross bar 44 to support the portions of the garments extending thereover when the frame and extension are in lowered position over the body of the case. With this bar intermediate the outer end of the extension of the outer end of the main frame, the bar supports the shorter portions of the garments which do not extend across the outer end of the extension and thus prevents such garment portions from falling through the open space in the extension. The bar 44 is preferably of wood or other light material and is fixed to the side arms 29 of the extension by metal fasteners in the same manner as used for the cross-bar 32 of the main frame. Any number of cross pieces could be added to the extension or the main frame or they could be omitted entirely without affecting the principles involved in the main frame and the method of carrying the garments.

The details of construction and arrangement of parts shown and described may be variously changed and modified without departing from the spirit and scope of my invention except as pointed out in the appended claims.

I claim as my invention:

1. A hand carried luggage case, comprising

hingedly connected body and cover sections, a garment carrying element pivotally mounted at its inner end in one of said sections and adapted to support garments in folded form over its outer end, means on the element whereby a plurality of garments may be attached thereto in superimposed relation, and cross-bars at the outer end of the element for individual folding thereover of the garments on the element, said bars being in spaced relation in the length of the element and in the plane thereof.

2. A hand carried luggage case, comprising hingedly connected body and cover sections, a garment carrying element pivotally mounted at its inner end in one of said sections and adapted to support garments in folded form over its outer end, means on the element whereby a plurality of garments may be attached thereto in superimposed relation, and cross-bars at the outer end of the element and in the plane thereof over which the garments are individually folded, one of said bars being fixed to the element and another bar having detachable connection therewith.

3. A hand carried luggage case, comprising hingedly connected body and cover sections, a garment carrying element pivotally mounted at its inner end in the cover section and adapted to support a garment in folded form over its outer end, a conventional form of garment hanger engageable with the element for attaching a garment thereto, a flexible curtain carried by the cover section and swingable over the outer side of the element when in the cover section for completely covering the garment and retaining the element and garment in the cover section, a rod carried by the curtain adjacent its outer end, and keepers carried by the element adjacent its inner end to releasably engage the rod.

WILLIAM WINTZ.
